UNITED STATES PATENT OFFICE.

REUBEN B. BENJAMIN, OF CHICAGO, ILLINOIS, ASSIGNOR TO BENJAMIN ELECTRIC MANUFACTURING COMPANY, OF CHICAGO, ILLINOIS, A CORPORATION OF ILLINOIS.

SWITCH SOCKET.

Application filed March 1, 1922. Serial No. 540,195.

My invention relates to switch sockets, and more specifically to switch sockets of the push-bar type.

One of the objects of my invention is to provide an improved push-bar switch socket which can be readily assembled and disassembled.

A further object of my invention is to provide a unit shell push-bar switch socket in which the interior construction is held in place in the unit shell casing by means of the push-bar.

A further object of my invention is to provide a switch socket which will be durable and efficient in use, simple in construction, and cheap to manufacture.

A further object of my invention is to improve certain features of switch construction.

20 Further objects will appear from the detailed description to follow and from the appended claims.

In the drawings in which an embodiment of my invention is shown—

25 Figure 1 is a side elevation of a push-bar switch socket;

Fig. 2 is a part sectional, part elevational view of the interior construction, removed from the unit shell casing;

30 Fig. 3 is a bottom plan view of the socket;

Fig. 4 is a top plan view of the interior construction;

Fig. 5 is a section on the line 5—5 of Fig. 4, but showing the parts in the casing;

35 Fig. 6 is a sectional view similar to Fig. 5 but showing the switch in a different position;

Fig. 7 is a section on the line 7—7 of Fig. 6;

40 Fig. 8 is a section on the line 8—8 of Fig. 5;

Fig. 9 is a section on the line 9—9 of Fig. 6; and

45 Fig. 10 is an unassembled view of parts of the switch.

Referring now to the drawings in detail, the construction shown therein comprises an insulating base 10 on which the switch mechanism 11, receptacle contacts 12 and 13, and wiring terminals 14 and 15 are mounted, a unit shell sheet metal casing 16 for housing the insulating base 10 and the parts supported thereby, and a transversely extending bar 17 which serves the double purpose

of operating the switch mechanism 11 and 55 holding the insulating base 10 with the parts supported thereby in the unit shell casing 16.

The entire interior construction, including the insulating base 10, the switch mechanism, contacts, and wiring terminals supported thereby, can be removed from the unit shell casing 16 through the open outer end thereof simply by loosening up the center contact screw 13 slightly, sufficiently to permit the transversely extending bar 17 to be drawn out laterally, permitting the entire interior construction to be slipped out through the open end of the casing. The unit shell casing 16 is provided with oppositely disposed lateral openings 18 and 19, through which the ends of the transversely extending push-bar extend, in position to be engaged for the operation of the switch mechanism. The opening 19 is made large 70 enough so that the push-bar 17 can be withdrawn through this opening, when the center contact screw 13 is screwed out sufficiently to permit such withdrawal. This center contact screw also serves to limit the to and fro movement of the push-bar, by the engagement of the shoulders 20 and 21 on the push-bar with the shank of the screw. The push-bar is recessed as indicated at 22 to permit the necessary to and fro movement for operating the switch mechanism. The push-bar 17 may be an insulating sheet fibre stamping, guided in slots or notches 23 and 24, in the insulating base 10, and held in place in these notches 90 by means of the fibre disc 25, which holds the threaded shell contact 12 in place.

The switch mechanism 11 comprises a sheet metal stamping 26, (Fig. 10) having a pair of switch blades or arms 27 and a 95 slide or shoe portion 28, and a coil compression spring 29 which holds the slide portion 28 of the stamping against the upper edge of the push-bar 17, as shown in Figs. 5 and 6. The push-bar 17 is provided with a cam 100 portion for engagement with the slide portion 28, this cam portion comprising two oppositely inclined portions 30 and 31 meeting at a crest 32. As the push-bar 17 is operated, the slide portion 28 rides up one 105 side of the cam and down the other. As the crest 32 passes the point of application of pressure of the spring 29, the slide 28 is

given a quick oscillation from a position in which it is in engagement with one of the inclined portions to a position in which it is in engagement with the other inclined portion. This quick oscillation of the slide 28 causes also a quick oscillation of the switch arm 27, to make or break the circuit. The spring 29 is seated in a recess in the insulating base 10, and is provided with a transversely extending bearing member 33, which is seated in the bearing notches 34 on the stamping 26. This transversely extending portion 33 also serves to guide the lower end of the spring, as it extends into oppositely disposed guide slots 35 in the insulating base 10.

The switch blade 27 controls the circuit between the wiring terminal 15 and the center contact 13. For this purpose, a pair of contact members 36 and 37 are provided, the contact 36 being electrically connected with the center contact 13, and the contact 37 being electrically connected with the wiring terminal 15. The contact 37 is formed as part of a sheet metal stamping, held in place by means of the screw 38, which extends upwardly through the insulating base 10, and is threaded into the binding plate of the wiring terminal 15. This screw 38 thus also serves to electrically connect the contact 37 with the wiring terminal 15. The contact 36 is formed as part of a sheet metal stamping 39 (Fig. 3) having a central portion into which the center contact screw 13 is threaded, and having oppositely disposed outwardly bent ears 40 which are bent over the fibre disc 25 to position the stamping and hold it in place. The stampings of which the contacts 36 and 37 are a part are insulated from each other and from the shell contact 12 by means of the insulating fibre disc 25.

When the contact blades 27 of the switch snap down into engagement with the contacts 36 and 37, the circuit is completed between these contacts 36 and 37, as the switch blades 27 are formed as part of a single sheet metal stamping. When the contact blades 27 snap out from between these contacts 36 and 37, the circuit is broken.

50 The threaded shell contact 12 is electrically connected with the wiring terminal 14 by means of a screw 41. The screw 41 together with the screw 42 serves to hold the threaded shell contact in place on the insulating base 10.

As stated above all that is necessary to do to take out the interior construction is to back out the center contact screw 13 sufficiently to free it from the notch 22 in the push-bar 17, and then to pull the switch bar 17 out through the openings 19. The entire interior construction can then be slipped out of the unit shell casing 16 for wiring, repairs, inspection, etc.

65 While I have shown but one form of my

invention, it is obvious that it may be embodied in other forms as covered and defined by the appended claims.

Having thus described my invention, what I claim as new and desire to secure by Letters Patent of the United States is—

70 1. A switch socket construction comprising a shell receptacle contact, switch mechanism, a transversely extending push-bar for operating said switch mechanism, and a screw for limiting the movement of said push-bar, the head of said screw being positioned to form a center receptacle contact.

75 2. A switch socket construction comprising an insulating base, a shell contact and switch mechanism mounted thereon, a casing open at one end for receiving said base, switch mechanism and contact, a transversely extending push-bar for operating said switch mechanism, said casing having an opening through which said push-bar extends, and a screw for holding said push-bar in assembled relation with respect to the switch mechanism, the head of said screw being positioned to serve as a center receptacle contact.

80 85 3. A switch mechanism comprising a switch blade, a push-bar, an elongated shoe extending longitudinally with respect to said push bar and a spring, said switch blade being secured to said shoe to move therewith, said push-bar having oppositely inclined portions meeting at a crest, the elongated shoe engaging said cam portion and being held thereagainst by said spring, whereby as said push-bar is moved, said shoe will ride up one incline, oscillate as the crest passes underneath the point of application of the spring pressure and then ride down on the other incline.

90 95 100 4. A switch socket construction comprising an insulating base, receptacle contacts and switch mechanism mounted on said insulating base, a casing open at one end for receiving said base, switch mechanism and contacts, common means for operating said switch mechanism and holding said base and the parts mounted thereon in said casing, said common means comprising a transversely extending push-bar, said casing having an opening through which said push-bar extends, said push-bar being removable laterally through said opening, and means accessible for operation through the open end of said casing for limiting the movement of said push-bar.

105 110 115 120 125 5. A switch socket construction comprising an insulating base, receptacle contacts and switch mechanism mounted on said insulating base, a casing open at one end for receiving said base, switch mechanism, and contacts, said casing having laterally oppositely disposed openings therein, means for operating said switch mechanism comprising a transversely extending push-bar extending through said openings and remov-

able through one of said openings, and means accessible for operation through the open end of said casing for limiting the movement of said push-bar.

5 6. A switch socket construction comprising an insulating base, receptacle contacts and switch mechanism mounted on said insulating base, a casing open at one end for receiving said base, switch mechanism and contacts, common means for operating said switch mechanism and holding said base and the parts mounted thereon in said casing, said common means comprising a transversely extending push-bar, said casing having an opening through which said push-bar extends, said push-bar being removable laterally through said opening, and screw means accessible for operation through the open end of said casing for limiting the 20 movement of said push-bar.

7. A switch socket construction comprising an insulating base, receptacle contacts and switch mechanism mounted on said insulating base, a casing open at one end for receiving said base, switch mechanism and contacts, said casing having lateral oppositely disposed openings therein, and means for holding said base and the parts mounted thereon in said casing comprising a 25 transversely extending push-bar extending through said openings and removable through one of said openings, and means accessible for operation through the open end of said casing for limiting the movement of said push-bar.

8. A switch construction comprising an elongated reciprocable push bar, a pair of contacts located on opposite sides of said push bar, and a pair of electrically connected oscillatable switch blades operated by said push bar and movable to a position in which they straddle the push bar to engage a pair of contacts respectively, an elongated shoe extending longitudinally with respect to said push bar on which said switch plates are mounted, said push bar having inclined portions meeting at a crest to form a cam, said elongated shoe engaging said cam, and a spring for holding said shoe against said cam whereby as said push bar is moved, said shoe will ride up one incline, oscillate as the crest passes underneath the point of application of the spring pressure and then ride down on the other incline.

9. A switch mechanism comprising a switch blade, a push-bar, an elongated shoe extending longitudinally with respect to the push-bar and formed integrally with said switch blade, and a spring, said push-bar having oppositely inclined portions meeting at a crest, the elongated shoe engaging said cam portion and being held there-against by said spring whereby as the push-bar is moved said shoe will ride up one incline, oscillate as the crest passes underneath the point of application of the spring pressure and then ride down on the other incline.

In witness whereof, I have hereunto subscribed my name.

REUBEN B. BENJAMIN.
